UNITED STATES PATENT OFFICE.

PATRICK M. WILLIAMS, OF NORTH WILKESBORO, NORTH CAROLINA, ASSIGNOR TO
L. MOORE DRY KILN CO., OF JACKSONVILLE, FLORIDA, A CORPORATION OF
FLORIDA.

VENEER KILN.

Application filed May 22, 1920. Serial No. 383,530.

To all whom it may concern:

Be it known that I, PATRICK M. WILLIAMS, a citizen of the United States, residing at North Wilkesboro, in the county of 5 Wilkes and State of North Carolina, have invented certain new and useful Improvements in Veneer Kilns, of which the following is a specification.

My invention relates to an improvement 10 in dry kilns and the present invention is more particularly adapted to the drying of veneer and is an improvement on the La Fayette Moore dry kiln system.

In the accompanying drawings 15 Figure 1 is a floor plan view.

Figure 2 is a longitudinal vertical section.

Figures 3 and 4 are opposite end views.

Figure 5 is a horizontal vertical section 20 of the heating end of the kiln showing a modified form of my invention disclosing a baffle to deflect the heat to the bottom of the kiln.

Figure 6 is a top plan view of the heating coil partially broken away, and

25 Figure 7 is a vertical section of another modification of the heating end of the kiln showing a pair of baffles to deflect the heat toward the bottom of the kiln.

A, represents the kiln. This may be built 30 on piers and longitudinal and transverse sills in the usual manner and it has a main track 1, running through it longitudinally substantially from one end to the other. At opposite ends of the track there are provided loading and unloading transfer tracks 35 2 and 3 respectively. Storage tracks 1^a may be provided at one side of the main track as shown in Figure 1. Doors 4, preferably of the sliding type, are provided for 40 closing the open ends where the transfer tracks are located.

A battery of heating coils 5, is located 45 at one end of the kiln and a suction fan or fans 6, at the opposite end as shown in Figures 1 and 2. The roof 7, of the kiln at the pipe end preferably slopes down so that the opening 8, for air at the heating end is comparatively restricted the object being to insure its being well heated during 50 its passage through the heating coils and the larger space within permits the heated and

dried air to expand and circulate rapidly through the length of the kiln under the influence of the suction fans 6, at the opposite end of the kiln.

The size of the opening 8, is regulated and controlled by doors 9, of which there are several, two being shown. These doors may be hinged or slide doors (not shown) and the idea is that the size of the opening 8, 55 may be varied according to the way these doors are adjusted and accordingly as a greater or less amount of air is to be sucked in through the opening 8.

At intervals within the kiln I propose to 60 arrange sets of doors or flaps 10, swung upon two-way hinges 10' their object being to close the space at the surrounding edges of the body 11, of lumber carried upon the loaded truck 12, so that the heated air, so far as possible is deflected and directed 65 through the spaces between the lumber and prevented so far as possible from passing around it.

Two sets only of these two-way doors or 70 flaps 10, are shown in Figure 1, but more or even less might be employed and they are located at top, bottom and on the side walls of the kiln and are of a width to fill 75 the space between the normal load of a truck and the roof, floor, and walls of the kiln, and these two-way doors or flaps are mounted on spring hinges and in position to be 80 swung aside by the truck and its load.

From the foregoing it will be seen that 85 the air immediately upon entering the kiln must come in contact with the coils; that the amount of air admitted may be regulated; that this air upon being heated and expanded is directed through the lumber and 90 prevented from circulating around it where its effect would be lost.

Either one or two suction fans or even 95 more might be employed, two only being shown. These are driven by belts 13 and 14.

While I have shown only three sets of coils at the pipe end it is obvious that even more or less may be employed; also that the dimensions of the kiln might be varied as 100 well as the material used in its construction without departure from my invention.

I claim,

A kiln having a heater at one end, suction means at the other, the heated end having an inlet opening of limited size, and a roof sloping away from said opening, whereby incoming air is forced to pass directly through and over said heater, and is per-

mitted to expand as it progresses from said opening into the kiln, and means for varying the amount of air sucked in through 10 said inlet.

In testimony whereof I affix my signature.

PATRICK M. WILLIAMS.
